UNITED STATES PATENT OFFICE.

CHARLES A. MEISEL, OF BOSTON, MASSACHUSETTS, ASSIGNOR TO MEISEL PRESS MANUFACTURING COMPANY, OF BOSTON, MASSACHUSETTS, A CORPORATION OF MASSACHUSETTS.

APPARATUS FOR PRINTING NUMBERED IMPRESSIONS.

Application filed January 10, 1923. Serial No. 611,901.

To all whom it may concern:

Be it known that I, CHARLES A. MEISEL, a citizen of the United States, and a resident of Boston, county of Suffolk, and State 5 of Massachusetts, have invented an Improvement in Apparatus for Printing Numbered Impressions, of which the following description, in connection with the accompanying drawings, is a specification, like 10 characters on the drawings representing like parts.

This invention relates to printing devices and more particularly to devices which are adapted to print a series of numbers on successive 15 impressions and the object more particularly is to provide an arrangement of this character which will provide for one or more supernumerary impressions between successive series of numbers without danger 20 of confusion.

My invention will best be understood by reference to the following description of an illustrative embodiment thereof taken in connection with the accompanying drawings, wherein:

Fig. 1 is a diagrammatic side elevation of portions of a printing press partly broken away to show the portion at the upper left hand part of the figure substantially on the 30 line 1—1 of Fig. 2;

Fig. 2 is a longitudinal section through the numbering head shaft;

Fig. 2^a is a detail;

Fig. 3 is a section on the line 3—3 of 35 Fig. 2;

Fig. 4 is a side elevation of a cam;

Figs. 5 and 6 are sections on the lines 5—5 and 6—6 of Fig. 2 respectively; and

Fig. 7 is a section on the line 7—7 of 40 Fig. 3.

Printing mechanisms for printing a series of consecutive numbers, as, for example, on a series of tickets or coupons, are well known as are also means for causing an intermission of the numbering operation between the printing of successive series. By way of example I will refer to the patent to Charles A. and Francis Meisel, 1,186,020, June 16, 1916, and the patent to Francis 45 Meisel, 1,034,637, August 6, 1912. In view of the art as disclosed particularly by these patents, the illustration and description of certain mechanisms herein will be consider-

ably abbreviated. By way of example we may consider the printing on a continuous 55 web of sets of coupons, the elements of each set of which are to be consecutively numbered, say from 1 to 100. That is, the first one hundred coupons will be numbered serially and then the numbering mechanism 60 will be manipulated to cause the series to repeat. To facilitate the separation of the coupons belonging to individual series for collection and assembly it is desirable to have a certain space between successive series 65 and this may be effected, as in the patents referred to, by stopping the operation of the numbering mechanisms so that the last number of the series will be repeated a certain 70 number of times. As a result of this 70 operation there are a number of waste or extra coupons in the series and to avoid confusion and also because what have herein been referred to as coupons may be certificates of value, I provide in accordance with 75 my present invention means for printing on these duplicate elements with an auxiliary printing device which may indicate that they are not true and valid elements of the 80 series but merely waste. In the example of 80 my invention here chosen for purposes of illustration the word "Void" is printed on the coupons of duplicate number.

Referring particularly to Figs. 1 and 2, I herein show certain elements of a numbering printing attachment bearing considerable resemblance to that shown in the patent to Francis Meisel 1,034,637 above referred to. Opposing a suitable impression cylinder 9 there may be arranged a shaft 11 carrying 90 a suitable number of numbering heads 13 of well known type. To cause the operation of these numbering heads so that they will print successive numbers each head or set of heads may be controlled by a cam arrangement embodying the relatively stationary member 14 and the slidable member 15 which are provided with the grooves 17 and 19 in the form of circular arcs. When the elements are spaced from each other 95 as in Fig. 1 the grooves 17 and 19 form an eccentric track adapted to actuate the pawl lever of the numbering head as described in the patents above referred to but if the member 15 is caused to approach the member 14 the two grooves will form a circular 100 105

track which will be without effect on the numbering head. The member 15 may be provided with a rack 21 which meshes with a toothed shaft 23 extending across the press 5 from one frame to another, the rack herein engaging with the underside of this shaft. If the shaft 23 is given a partial rotation clockwise from Fig. 1 the cam section 15 will be moved to the left and the operation 10 of the numbering head will be stopped and until the reverse action takes place the same number will be printed repeatedly. Herein the shaft 23 projects at the side of the machine and provides at the outer end a pinion 15 with which meshes a sector gear lever 25 which may be rocked by the lever arm 27 having a nose or follower 29 cooperating with a cam 31 toward which the lever is 20 pressed by a spring 33. The cam 31 is provided with a depression 35 into which the nose 29 may drop and when this occurs the arm 27 will swing counterclockwise as will the sector 25 and the pinion shaft 23 will be rotated. The cam 31 is rotated by a 25 ratchet wheel 37 operated by a pawl 39 on the pawl-carrying lever 41 which is intermittently oscillated by connecting rod 43 from a crank on the impression cylinder 9. On each rotation of the impression cylinder 30 9 and in definite relation to the number of impressions the ratchet wheel and consequently the cam 31 is incrementally advanced and thus after a certain number of 35 impressions has been made and the desired numerical series is completed the notch 35 in the cam will come opposite the follower or nose 29 and the mechanism will be operated to shift the cam part 15 and stop the operation of the numbering head which will then print the same number repeatedly for 40 a certain number of impressions until the follower or nose 29 rides out of the recess 35 after which the series will be repeated. In the drawing I have also illustrated a 45 manual adjusting means substantially as shown in the patent to Francis Meisel, No. 1,034,637, above referred to.

In accordance with my invention I provide a suitable printing mechanism governed 50 in opposite phase to the numbering head or heads to print suitably on the work when the numbering head is no longer operating and is printing duplicate numbers. Referring particularly to Figs. 2 and 6 in the present embodiment of my invention I have 55 shown a cylinder or wheel 45 mounted on the numbering head shaft 11 and opposing the impression cylinder 9 and mounted radially in this wheel 45 are provided type-carrying 60 plungers 47 which may carry suitable printing types 49 on their faces and herein I have shown such a type bearing the legend "Void" as shown in Fig. 2a. In the embodiment of 65 the invention shown four impressions are made or four coupons or the like printed on

each revolution of the printing couple and I therefore show here four type-carrying plungers. These plungers 47 are provided with stems 51 having heads 53 on which act helical springs 55 normally tending to draw the plungers radially inwardly to a position in which they will not print as they pass the impression cylinder and means are provided whereby the plungers may be forced radially outwardly at proper times 70 to permit them to act. In the present instance this may be effected by means of cams acting on the heads 55 of the plungers and which may take the form of rods or shafts 57 housed in suitable grooves in the numbering head shaft 11 and having flattened sides 59 as best shown in Fig. 6. It will be understood from that figure that if the flattened sides of these rods are presented to the heads 55 the springs will draw the plungers inwardly and the types will be in inoperative position but if the rods are turned as shown at the left of Fig. 6 the plungers will be forced outwardly and the types will be in 80 operative position.

This operation of the plungers is effected in opposite phase with the control of the numbering head through the cam grooves 17 and 19 and conveniently through the same pinion shaft 23 and for this purpose the ends of the rods 57 may be formed as pinions 61 (see Figs. 2 and 7) and may be rocked by segments 63 pivoted on a collar or flange 65 carried by the shaft 11 and adapted to be operated by the levers 67 carrying cam rolls 69 and suitable cam means such as I will hereinafter describe may act on the cam rolls 69 at proper times governed by the turning of the pinion shaft 23. Referring now more particularly to Figs. 2, 3 and 7, I may mount a holder 71 on a sleeve or bushing 72 surrounding the end of the shaft 11 which may be provided with a dovetailed groove 73 (see Fig. 3) adapted to receive a corresponding rib on a slidable cam holder 75 conveniently of crescent or partly annular form to adapt it partly to embrace the shaft 11 as shown in Fig. 2. The cam holder has an arm carrying a rack 77 meshing with the pinion shaft 23 preferably at 100 the upper side thereof so as to be operated in opposite phase to the rack 23 controlling the numbering head.

Carried by the cam holder 75 conveniently at the inner side thereof is a cam 79 shown by itself in Fig. 4 and which may embody a plate of partially annular shape conveniently provided on its inner circumference with a flange 81 (see Fig. 7) facilitating its support on the cam holder 75. The inner face of the plate 79 carries two camming elements disposed generally on opposite sides of the path of the cam roll 69, an inner element 83, conveniently braced by the rib 85, and an outer element 87. In the 110

inner position of the cam holder 75 the cam rolls or followers 65 miss the inner cam 83 but are forced inwardly by the cam 87 and the rods 57 are rocked to the position shown at the right and top of Fig. 6 wherein the types 49 are drawn inwardly to an inoperative position and will not cooperate with the impression cylinder 9. This is the normal position of the parts while the numbering operation proceeds. When, however, the pinion shaft 23 is rotated to shift the cam controlling the numbering heads so that a number is repeated, the clockwise revolution of the shaft 23 viewing Fig. 3 will draw the cam holder 75 and its cam toward the right and the cam rolls 69 will then miss the cam 87 but will come in contact with the cam 83 which will cause the rods 57 to be rocked to the position shown at the bottom and left of Fig. 6 projecting the printing types 49 out to a printing position. When the serial printing of numbers is resumed, the cam holder is shifted back to the left and the cam element 87 acts to retract the printing types 49 again. In Figs. 3 and 6 we may imagine that this operation has just taken place and that the printing of a series of numbers is to recommence after a half revolution of the printing couple. Before the cam was shifted all the printing types were at their outward position but the plungers shown at the top and left after having printed have now been acted upon by the cam element 87 and are retracted. The type carried by the plunger shown at the bottom of Fig. 6 is about to print and after it has done so it also will be retracted as will the plunger shown at the left. After the series of numbers have been printed and the cam element 83 is brought into operative position to act on the cam roll 69, each plunger is moved to outward position substantially as it passes the three o'clock position in Fig. 6 and prints as it reaches the six o'clock position.

I have described in detail the particular mechanical elements which are utilized in the embodiment of my invention here shown. Obviously these are merely exemplary of suitable means for performing the required functions and are not essential to the invention in its broader aspects. What I do claim as new and desire to secure by Letters Patent I shall express in the following claims.

55 Claims—

1. Printing mechanism comprising a numbering head, a shiftable cam controlling the operation of the same, an auxiliary printing attachment, a shiftable cam controlling its operation and means governing said cams in opposite phase.

2. Printing mechanism comprising shiftable types governed to print a series of numbers and to repeat a number of the series, a cooperating printing mechanism and

means for bringing it into printing position when the types repeat the printed number.

3. In a mechanism of the class described in combination with a numbering head, its operating cam and controlling means therefore, a retractile printing member and means operating the same comprising a cam follower and a cam movable to cooperate with the follower.

4. In a mechanism of the class described in combination with a numbering head, its operating cam and controlling means therefore, a retractile printing member and means operating the same comprising a cam follower and a cam movable by the said controlling means to bring it into cooperating relation to the follower.

5. Printing mechanism of the class described comprising a rotatable form element including a numbering head, an eccentrically expandible cam for operating the same having a sliding part, a printing device and means for protracting the same including a sliding cam-carrying element, 85 racks on the sliding elements and a pinion shaft, the rack of the numbering head and the rack of the cam-carrying element engaging therewith on opposite sides respectively. 90

6. Printing mechanism of the class described comprising a rotatable form element including a numbering head, an eccentrically expandible cam for operating the same having a sliding part, a printing device and means for protracting the same including a sliding cam-carrying element and a common mechanism connected to said parts to slide the cam-carrying element into and from operative position when it contracts and expands the numbering head cam respectively. 100

7. Printing mechanism comprising a rotatable shaft, a substantially radial type-carrying plunger extending therefrom, a 110 rod extending along the shaft and having a portion formed as a cam opposing the plunger and a portion formed as a pinion, a segment engaging the pinion and means for rocking the segment comprising a trip 115 movable to and from operative position.

8. Printing mechanism comprising a rotatable shaft, a substantially radial type-carrying plunger extending therefrom, a rod extending along the shaft and having a portion formed as a cam opposing the plunger and a portion formed as a pinion, a segment engaging the pinion, means for rocking the segment comprising a cam and means controlled by the number of impressions for moving the cam into and out from operative position.

9. Printing mechanism comprising a numbering head, a numbering head cam having a movable portion provided with 130

a rack, a pinion shaft meshing with the rack, a master cam, means for advancing the same as the printing proceeds and means controlled by the master cam for rocking the pinion shaft.

10. Printing mechanism comprising a numbering head, a numbering head cam having a movable portion provided with a rack, a pinion shaft meshing with the rack, a master cam, means for advancing the same as the printing proceeds, a lever controlled by the master cam and a sector moved thereby for rocking the pinion shaft.

11. A cancelling attachment for a numbering head shaft comprising a carrier having a protractable type element and mechanism for protracting the same including a follower and a shiftable trip for cooperation with the follower having means for supporting it adjacent the shaft and means for coupling it with the control for the numbering heads.

15 20
In testimony whereof, I have signed my name to this specification.

CHARLES A. MEISEL.
